(57) **CLAIM**

The ornamental design for an image input device, as shown and described.

DESCRIPTION

FIG. 1 is a perspective view of the image input device; FIG. 2 is a top view thereof; FIG. 3 is a left side view thereof; FIG. 4 is a right side view thereof; FIG. 5 is a rear view thereof; FIG. 6 is a front view thereof; and, FIG. 7 is a bottom view thereof.

The broken line showing in FIG. 5 is for illustrative purposes only and forms no part of the claimed design. In addition, the broken lines in FIG. 5 define the bounds of the claimed design and form no part thereof.
